US0D1112110S

(12) **United States Design Patent** (10) **Patent No.:** **US D1,112,110 S**
(45) **Date of Patent:** ** *Feb. 10, 2026

(54) **CONTROL DEVICE**

- (71) Applicant: **Lutron Technology Company LLC**,
Coopersburg, PA (US)
- (72) Inventors: **Gregory Altonen**, Easton, PA (US);
Susan Hakkarainen, Doylestown, PA (US); **Jason C. Killo**, Emmaus, PA (US); **Brad Michael Kreschollek**, Bethlehem, PA (US); **Matthew Philip McDonald**, Phoenixville, PA (US)
- (73) Assignee: **Lutron Technology Company LLC**,
Coopersburg, PA (US)
- (*) Notice: This patent is subject to a terminal disclaimer.
- (**) Term: **15 Years**
- (21) Appl. No.: **29/986,071**
- (22) Filed: **Jan. 17, 2025**

Related U.S. Application Data

- (63) Continuation of application No. 29/911,688, filed on Sep. 7, 2023, now Pat. No. Des. 1,060,276, which is a continuation of application No. 29/858,746, filed on Nov. 3, 2022, now Pat. No. Des. 1,001,751, which is a continuation of application No. 29/785,356, filed on May 25, 2021, now Pat. No. Des. 969,756, which is a continuation of application No. 29/724,257, filed on Feb. 13, 2020, now Pat. No. Des. 922,336, which is a continuation of application No. 29/655,299, filed on Jul. 2, 2018, now Pat. No. Des. 878,309, which is a continuation of application No. 29/594,202, filed on Feb. 16, 2017, now Pat. No. Des. 837,169.

(57) **CLAIM**

The ornamental design for a control device as shown and described.

DESCRIPTION

FIG. 1 is a front perspective view of a control device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines depict portions of the control device which form no part of the claimed design.

1 Claim, 4 Drawing Sheets
